(57) **CLAIM**

We claim the ornamental design for a garage door opener, as shown and described.

DESCRIPTION

FIG. 1 is a perspective view of a garage door opener according to our new design;

FIG. 2 is a bottom view of the garage door opener of FIG. 1;

FIG. 3 is a top plan view of the garage door opener of FIG. 1;

FIG. 4 is a rear elevational view of the garage door opener of FIG. 1;

FIG. 5 is a front elevational view of the garage door opener of FIG. 1;

FIG. 6 is a right-hand side elevational view of the garage door opener of FIG. 1; and,

FIG. 7 is a left-hand side elevational view of the garage door opener of FIG. 1.

The broken line showing is for illustrative purposes only and forms no part of the claimed design.
